INVENTOR
ALBERT GUDEMAN.
By J. M. Thurston, Atty.

UNITED STATES PATENT OFFICE.

ALBERT GUDEMAN, OF EUREKA, ILLINOIS.

FILTER.

SPECIFICATION forming part of Letters Patent No. 546,527, dated September 17, 1895.

Application filed April 18, 1895. Serial No. 546,289. (No model.)

To all whom it may concern:

Be it known that I, ALBERT GUDEMAN, a citizen of the United States, residing at Eureka, in the county of Woodford and State of Illinois, have invented certain new and useful Improvements in Filters; and I do hereby declare that the following is a full, clear, and exact description of the invention, which will enable others skilled in the art to which it appertains to make and use the same.

This invention relates to filters, and more particularly to that class of filters which are used for cisterns and other outdoor work.

The object of the herein-described device is to catch and filter perfectly the rain-water as it comes from the roofs of buildings, &c.

In the drawings herewith, Figure 1 represents a side elevation of the filter, showing the interior, one side being removed. Fig. 2 is an edge view of the filter, showing the interior through an open door. Fig. 3 is a perspective view of a tray used in the filter. Fig. 4 is a detail in section of a portion of said tray.

The filter-casing is shown at A and is made in rectangular form, but may be made in any form desired. The interior of the filter is reached by opening the door B on one end of the casing. The top of the casing is provided with a lifting door or lid C. This door forms a part only of the top of the filter-casing. The fixed portion of the top carries or has opening into it a pipe D, which delivers the water to be filtered.

A strainer E is placed under the top of the filter and under the pipe D. Under the said strainer is fixed a board F, which may or may not be parallel with the said strainer E.

A drain-spout G is secured to and opens through the door B and is placed to receive any foreign matter and deliver it outside the filter.

Beneath the board F, which slants substantially as shown, is placed a tray H, which slants in the opposite direction to the board F. The lower end of the tray H is provided at the bottom with an opening and a short spout H' to allow water to pass through. A strainer or sieve H² is secured in the end of the tray above the said opening and spout H' in any suitable manner and position. The tray is filled with charcoal of medium size or

with any other suitable filtering material. Below this tray H is located a second tray I, which slants in the reverse direction to that of the tray H and carries its spout H' at the opposite end—i. e., the end having the lowest level. This tray is filled with a slightly-finer grade of charcoal or other material having filtering capacity. The remaining space below the trays is filled with a series of trays similar to those described, and all slant in alternate opposite directions, and are each provided with finer filtering material as the bottom is reached.

The lower tray opens into and deposits the filtrate upon the bottom J of the filter, and from thence the said filtrate escapes through the pipe K to the cistern or other receiver.

The trays may be made of wood or metal, galvanized iron being preferable, and may be mounted on slides similar to drawers, if desired, and so arranged as to be easily drawn out separately or as a whole from the casing.

The filtering material may be placed in a spirally-winding tray running from the top to the bottom of the casing, or the tray may be made in any shape desired which will properly convey and filter the water. This is excellent for filtering all other fluids.

The operation of the device is as follows: The water entering the filter from the spout or pipe D at the top drops upon the strainer E first, and on passing through this all rubbish and insects are kept from passing farther, and the spout G serves as an exit for the same. Water on passing through this strainer falls upon the inclined board F. Passing down this, it runs into the tray H and down through the charcoal to the next tray below, &c., until at the bottom the water is perfectly clear and free from all foreign matter.

What I claim as new, and desire to secure by Letters Patent, is—

In a filter, the combination of the casing A substantially of the form shown, a lid C, a conduit passing through the top of said casing, an outlet pipe in the bottom of casing, an inclined strainer placed beneath said conduit, a spout at the lower end of said strainer, a drain board F placed beneath and parallel with said strainer substantially as shown, a series of filtering trays below said drain or running board substantially in the manner

shown and described, said trays being slanted in alternate directions and having an opening in the lower extremities thereof, a strainer covering said openings, a filtering material placed in said trays and all arranged substantially in the manner and for the purposes set forth and described.

In testimony whereof I affix my signature in presence of two witnesses.

ALBERT GUDEMAN.
